UNITED STATES PATENT OFFICE.

CHARLES FREDERICK ROCKSTROH, JR., OF RICHMOND HILL, NEW YORK, ASSIGNOR TO F. WESEL MANUFACTURING COMPANY, OF BROOKLYN, NEW YORK, A CORPORATION OF NEW YORK.

PRINTING-PLATE HOLDER AND REGISTERING CLAMP.

1,071,349.

Specification of Letters Patent. Patented Aug. 26, 1913.

Application filed June 2, 1911. Serial No. 630,842.

To all whom it may concern:

Be it known that I, CHARLES F. ROCKSTROH, JR., a citizen of the United States, residing at Richmond Hill, in the county 5 of Queens and State of New York, have invented certain new and useful Improvements in Printing-Plate Holders and Registering Clamps, of which the following is a specification.

10 The invention relates to means for holding and registering stereotype, electrotype and other printing plates and particularly to that class of clamping device which is employed with a bed or base provided with 15 a plurality of grooves in its upper surface to which the plate holding and registering hooks or clamps are let down and lifted bodily out of the same. These plate engaging or clamping devices are often known in 20 the trade as "register hooks."

Another feature of the invention resides in the making of the clamping device a unitary structure and locating the actuating parts within the body portion thereof, 25 thereby forming a construction in which all of the actuating parts are protected from dust and ink and whereby they are less liable to become injured by contact with any object when the clamp is removed from the 30 base or bed.

As showing a specific embodiment of the invention reference is made to the drawings forming a part of the specification in which—

35 Figure 1 shows a bed or base provided with a printing plate secured in place thereupon by register hooks. Fig. 2 shows a side elevation of the register hook. Fig. 3 shows a longitudinal section through the center of a 40 register hook taken on the line 3—3 of Fig. 5, the hand operating means being in operating position thereupon. Fig. 4 is a transverse sectional view taken on the line 4—4 of Fig. 2 looking in the direction of the arrows. Fig. 5 is a plan view of the register hook shown in Fig. 2. Fig. 6 is a longitudinal section of a modified form showing a swiveled plate engaging member or clamping jaw located upon the body portion of 50 the hook. Fig. 7 is a section of a cylindrical base showing another form of register hook which may be used in combination

with such a base. All the figures of the drawings with the exception of Fig. 1 are enlarged views.

The reference character 1 indicates the bed or base and is provided in its upper surface with a plurality of grooves or channels 2 of a predetermined depth and width. These grooves preferably have parallel 60 straight smooth side walls which permit the ready removal therefrom and insertion of the register hook hereinafter described which also has parallel sides. The grooves 2 are so arranged that a printing plate can 65 be secured in any desired position upon the base.

In the bottom of each of the grooves there are equally spaced holes or cavities 3 which may extend entirely through the base or to 70 only a predetermined depth. These holes are preferably enlarged at the bottom as by the counterbore 4 which is shown in Fig. 7. The clamping and registering device which as above stated is often termed a "register 75 hook", comprises a body or body member 5, a rack bar or base engaging hook member 6, a pinion 7, a worm 8 and a clamping jaw or plate engaging member 9. This clamping jaw or plate engaging member is 80 generally provided with an under beveled edge to directly engage the beveled edge of the printing plate so as to clamp and position the latter upon the base.

The body 5 is provided with a T-shaped 85 groove in the lower portion thereof and in this groove there is mounted the rack or base engaging member 6 so that the base can slide longitudinally relative thereto. This rack or base engaging member 6 is provided with downwardly extending base engaging portions or legs 9 which are enlarged at their lower ends and which serve as means for holding the register hook in place upon the base when located within the 95 openings or cavities 3 of the base.

The body member is counter-bored from one side and in this counter-bore there is located the pinion 7 meshing with the rack. In the form shown in Figs. 2 and 3 there is 100 also another counter-bore made in the base from the lower side and in this counter-bore the worm 8 is inserted so that it can mesh with the pinion 7 and serve when ac-

tuated to cause relative movement between the body portion and the rack and also to hold the rack and base in proper position relative to each other when not actuated. In this form the worm is retained in position in the base by means of the pin 10. The counter-bore in which the pinion 7 is located is closed after the pinion 7 is in place by means of the plate 11 held in the base by upsetting the metal as at 12.

10 The worm wheel 8 is provided with a square recess portion for the reception of an end of the operating tool 14. The method of operating the device is as follows: First, 15 the register hook is placed in one of the slotted portions 2 of the base and the base engaging portions or legs 9 of the base engaging member are passed through the cavit al portions 3 adjacent to the plate to be clamped or positioned on the base. Now by 20 merely turning the worm 8 by means of the hand operating tool 14 it will be apparent that the body portion carrying the clamping jaw will be moved along the slot and the 25 plate can thus be securely held in the desired position on said base.

In the form shown in Fig. 6 instead of making the counter-bore for the worm extend inwardly from the lower portion of 30 the base it is caused to extend inwardly from the upper portion and the clamping jaw or plate engaging member is provided with a projection 14 which is cut out at 15 so as to form a collar and this projection 14 enters the upper portion of the counter-bore. 35 This jaw is held in place on the body by means of pins 16 passing through the cut out portion 15 with which the collar of the projection engages. It will thus be apparent 40 from an inspection of this figure that a constriction has been devised which permits the clamping jaw or plate engaging member to assume any angular position. This 45 clamping jaw is also provided with an opening 17 through which the operating tool 14 can pass to the worm.

In Fig. 7 the bed or base is a portion of a cylinder which is provided with diagonal grooves upon its surface and of course the 50 contour of the register hook must be shaped so as to fit easily within the grooves and permit of the same being readily inserted or removed therefrom. In this form the base engaging portions or legs 9 are shaped 55 so that there is a hook extending in only one direction. This hook is indicated by 18. In order to prevent the register hooks from dropping from the cylinder there is provided 60 springs 19 that normally force the base engaging members carried by the rack forward sufficiently to prevent any disengagement between the base and said members. When 65 the holes 3 pass entirely through the base it will be apparent that any ink or dirt which may have collected in the lower por-

tion of the grooves can pass or be forced through said holes and will thus be less liable to clog the grooves.

It will be observed that the rack portion of the base engaging member 6 does not extend the full length of said member and that the parts 20 at the extremities thereof can serve as stop means when either one of said parts 20 engage the pinion 7. It will also be observed that the range of movement of the rack member 6 is greater than the distance between the holes 3.

It is obvious that various forms and modifications may be made without departing from the spirit and scope of the invention.

I claim as my invention:

1. In a device of the class described, the combination of a body carrying a plate engaging member at the top portion thereof, a hook member which also is carried by the body for engaging the base and means for causing relative longitudinal movement between the plate engaging member and the hook member.

2. In a device of the class described, the combination of a body, a plate engaging member, a rack mounted in the body and means for causing sliding movement between the rack and the body; the member, rack and means all carried by the body, the rack having a hook shaped holding means extending downwardly and below the body.

3. The combination of a base having holes or cavit al portions therein for the reception of hook-shaped holding means and a register hook, said register hook comprising a body carrying a plate-clamping or engaging member and having secured therein a base engaging member having hook-shaped means which enter said cavit al portions, and means for causing relative longitudinal movement between the base engaging member and body and for holding them in proper position relative to each other.

4. The combination of a slotted base having spaced holes or cavities along the lower portion of the slots and a register hook comprising a base, a plate engaging member, a rack, and gear means comprising a worm for causing relative movement between the base and rack; said rack having a base engaging portion for entering the holes and holding the register hook on the base. the the body, rack and gear means can all be lifted bodily out of the slot.

5. The combination with a body having at its upper portion a plate-engaging member, of a rack secured in the lower portion of the body and gearing for moving the body relative to the rack, said gearing comprising a pinion meshing with the rack and a vertically extending worm for operating the pinion and for holding the gear in any desired position, the rack having downwardly extending hook-shaped holding means.

6. In a register hook for use with bases for supporting printers' plates, the combination with a body member having parallel sides, said body member carrying a plate engaging member at the top portion thereof, of a rack held by and between the sides and gear means for moving the body member relative to the rack; said rack having a member or members constructed so as to engage a base and so as to hold the register hook in position thereupon, said rack also having secured thereto a spring which maintains said rack in holding position.
7. The combination of a base and a register hook having a body, a plate engaging member and a base engaging member having a portion extending downwardly beneath the body, said downwardly extending portion having at one side thereof a hook and at the other side a compression spring for maintaining the hook in engaging position upon the base, the body carrying the plate-engaging member and being horizontally adjustable along the base-engaging member.
8. The combination of a base having holes therein and a register hook comprising a plate-engaging jaw and a horizontally extending member along which the jaw is adjustable, said member having downwardly extending hook-shaped base engaging portions which enter the holes and hold the register hook in position on the base.
9. A device for securing printing plates to a base, said device comprising in combination a body having a plate engaging jaw and a rack along which the body slides, the rack being provided with hook means which engage the base for holding the device in place on the base and the body being secured to the rack so as to permit movement along the rack.
10. In a register hook, the combination with a body carrying a plate engaging jaw at the top portion thereof, a longitudinally extending rack to which the body is secured and along which the body can slide, means for causing the body to move along the rack and means connected with the rack so as to hold the rack in place against a force tending to lift the rack.
11. The combination of a base having spaced holes and a register hook having a body portion carrying a member relative to which the body can slide, said member being provided adjacent the ends thereof with hook-shaped base engaging means for holding the register hook in position on the base, the range of relative movement between the body portion and member being greater than the distance between the holes.
12. A register hook comprising a body portion having a plate-engaging jaw, a rack secured to the body portion, and means for causing the body portion to move along the rack, said rack being provided with hook-shaped base-engaging portions.
13. A device for securing printers' plates to a base comprising in combination with a body having at its upper portion a plate-engaging member, of a rack secured in the lower portion of the body and gearing for moving the body relative to the rack, said rack having downwardly extending base engaging means, and a spring secured to the rack for maintaining it in position on the base.
14. A printer's plate holding device comprising a body having at its upper portion a plate engaging member, a rack secured to the body and means for moving the body relative to the rack, said rack having a base engaging member and a spring secured thereto.
15. In a register hook, the combination of a body member carrying a plate engaging jaw, a longitudinally extending member and means for moving the body member along the same, the longitudinally extending member being provided with a base engaging member and also having secured thereto a movable member for maintaining the longitudinally extending member in position on the base.

This specification signed and witnessed this 17th day of May, A. D. 1911.
